US00D369141S

United States Patent [19]

Hayashi

[11] Patent Number: Des. 369,141

[45] Date of Patent: **Apr. 23, 1996

[54] **APPARATUS FOR WIRING CONNECTION
ON PRINTED WIRING BOARD**

[75] Inventor: **Akihiko Hayashi**, Kawasaki, Japan

[73] Assignee: **Mac Eight Co., Ltd.**, Yokohama, Japan

[**] Term: **14 Years**

[21] Appl. No.: **35,711**

[22] Filed: **Mar. 6, 1995**

[30] **Foreign Application Priority Data**

Dec. 7, 1994 [JP] Japan 6-37397

[52] U.S. Cl. **D13/133**

[58] Field of Search D13/133; 439/49,
439/76.2, 70, 571
